A. F. ERICKSON

VALVE

Filed Jan. 31, 1924

INVENTOR
ARTHUR F. ERICKSON
BY
C. F. Blake
Atty

UNITED STATES PATENT OFFICE.

ARTHUR F. ERICKSON, OF PORTLAND, OREGON.

VALVE.

Application filed January 31, 1924. Serial No. 689,796.

To all whom it may concern:

Be it known that I, ARTHUR F. ERICKSON, a citizen of the United States, residing at Portland, county of Multnomah, State of Oregon, have invented certain new and useful Improvements in Valves, of which the following is a specification.

My invention relates to valves in general, and particularly to electrically operated valves, and is a further development of and improvement upon that device disclosed in my Patent No. 1,439,231 of Dec. 19, 1922, the object being to improve the valve by the elimination of the upper valve seat, to simplify the electrical operating mechanism, and to inclose said mechanism within a gas tight casing.

I accomplish these objects by means of the construction illustrated in the accompanying drawing, which is a part of this application for Letters Patent, like characters of reference indicating like parts throughout the several views thereof, and in which:

25 Fig. 1 is a sectional elevation of my device.

Fig. 2 is a plan view thereof, with the cover removed.

30 Fig. 3 is an enlarged detail view of the valve and its connected parts.

Fig. 4 is a perspective view of one of the toggle arms and its fulcrum mounting.

In general my device consists of a valve of the globe valve type with a ball valve 5 cooperating with a metal seat therein; a pair of axially alined solenoids mounted within a gas tight casing secured to the body of the valve; a valve stem projecting through said solenoids; a plunger common 40 to both solenoids freely mounted upon said valve stem with its longitudinal movement thereupon restricted; and yieldable toggle mechanism within said casing and connected with said valve stem to accelerate the movement of the same and to hold the same at either end of its path of travel independently of the solenoids.

The valve body 5 is preferably of the globe valve type as shown, having a ground 50 metallic seat 6 upon which is seated a ball valve 7. Said ball valve is freely mounted upon a valve stem 8 so that it may have a limited movement in all directions independently of any movement of the stem. 55 This I accomplish by soldering, or otherwise securing, a flange 9 upon the ball valve 7,

and securing said flange to the stem 8 by means of a pin 10. The stem 8 is a loose fit within the flange 9, and the pin 10 is a loose fit within the stem 8, as shown in detail in Fig. 3, and thus the ball valve 7 is allowed a limited movement independently of the stem 8.

Mounted upon the valve body, by means of a nut 11 is a plug 12, which fits the valve body with a gas tight ground joint, preferably conical, as shown in Fig. 1. A centrally disposed tube 13 is secured to the plug 12, and is axially alined with the seat of the valve 7, and extends above the plug 12. An outer shell 14 surrounds the tube 13 and is spaced apart therefrom. Said casing is secured to the plug 12 in a gas tight manner. This is accomplished, preferably, by making the casing of cylindrical form, and providing a flanged or dished washer 15 at the lower end thereof, said casing and washer being soldered together, and said washer being soldered upon the plug 12.

A pair of axially alined solenoids 16 and 17 are disposed within the casing 14 and surrounding the tube 13, and the valve stem 8 passes upward through said solenoids to terminate above the same in a grooved end, as shown in Figs. 1 and 3. The solenoids are provided with a common plunger, which is of tubular form as shown at 18, and which is freely mounted upon the valve stem 8. The plunger 18 is positioned upon the stem 8 by means of a pin 19 secured in said stem, and the plunger is given a limited longitudinal movement range upon the stem 8 by making the orifices 20 in said plunger, which receives the pin 19, slightly larger than said pin.

The casing 14 extends beyond the solenoids to form a chamber, preferably at the upper end thereof, as shown in Fig. 1, and within said chamber is disposed the yieldable toggle mechanism. This consists of a pair of toggle arms 21 coacting with the slot 22 in the upper end of the valve stem 8, and having yieldable fulcrum brackets 23 secured upon a diaphragm 24 which diaphragm closes the casing 14 above the upper solenoid 17, and forms the bottom of the chamber within which the toggle mechanism is disposed. Electrical contact members 25 and 26 are mounted upon diaphragm 24, the contact member 25 being adapted to contact with one of said toggle arms 21

when the same is in its uppermost position, and the contact member 26 being adapted to contact with the other toggle arm when the same is in its lowermost position. Electrical binding posts 27 and 28 are mounted upon the casing 14 and insulated therefrom, as shown in Fig. 1. The binding post 27 is connected with the solenoid 16 by wire 29, and the binding post 28 is connected to solenoid 17 by wire 30. The solenoid 16 is connected to contact member 26 by wire 31, and the solenoid 17 is connected to contact member 26 by wire 32. Thus binding post 27, solenoid 16 and contact member 25 are in series, and also the same is true of binding post 28, solenoid 17 and contact member 26.

The casing 14 is closed at the top thereof in a gas tight manner, preferably by soldering thereupon a flanged or dished cap 33, and a grounded electrical binding post 34 is provided upon said cap.

The toggle arms 21 are mounted upon their respective brackets 23 in any convenient manner. As shown the arms are provided with a tongue 35 disposed within a slot in the upper ends of the brackets, the shoulders of the arms being disposed within indentures 36 in the brackets. The brackets are made of spring material, and thus sufficiently yieldable to enable the toggle mechanism to function.

The device is intended to be operated by a thermostat such as is commonly used with gas heating apparatus, and is so well known in the art as not to require illustration or description. My device is connected to one side of such a thermostat by wire 37, and to the other side of the thermostat by wire 38. Wire 39 is connected to the base of the thermostat through a battery or other convenient source of electric current. The device may also be operated by push buttons instead of a thermostat, such push buttons being inserted in the lines of the wires 37 and 38 in a manner too well known to need illustration herein.

The operation of my device is as follows.

With the valve closed as shown in Fig. 1, the thermostat operates to energize the wire 38, and the electric current flows therefrom through binding post 28, solenoid 17, contact member 26, diaphragm 24, casing 14 and binding post 34 to wire 31 and back to the thermostat. The solenoid 17 is thus energized, which causes the plunger 18 to move upward. Due to the lost motion between the pin 19 and the orifice 20, the plunger moves freely at first, and thus hits the pin 19 a slight blow, which assists in opening the ball valve 7. As the valve stem 8 is thus moved upward the toggle arms

pass their center, and then accelerate the movement of the valve and valve stem, terminating the movement thereof with a snap action, and finally holding the valve stem 65 in its uppermost position and thus holding the valve open.

When the valve is open the contact member 25 is in contact with the arm 21, and the contact member 26 is not in such contact. 70 If then the thermostat energizes the wire 37, the current will flow therefrom through binding post 27, wire 29, solenoid 16, wire 31, contact member 25, diaphragm 24, casing 14 and binding post 34 to wire 31 and 75 back to the thermostat. The solenoid 16 is thus energized, which causes the plunger 18 to move downward. Due to the lost motion between the pin 19 and the orifice 20 the plunger moves freely at first, and thus hits 80 the pin 19 a slight blow, which assists in overcoming the resistance of the toggle mechanism, and closes the valve. As the valve stem 8 thus moves downward, the toggle arms pass their center, and then accelerate the movement of the valve and valve stem, terminating the movement thereof with a snap action, and finally holding the valve 7 firmly upon its seat within the valve body 5. 90

My device may be made of any size, and constructed of any materials deemed convenient and suitable for a device of this character, and while I have illustrated and described a form of construction and arrangement of parts found desirable in materializing my invention, I wish to include in this application all mechanical equivalents and substitutes that may fairly be considered to come within the scope and 100 purview of my invention as defined in the appended claim.

Having disclosed my invention so that others may be enabled to construct and to use the same, what I claim as new, and desire to secure by Letters Patent is:

In a valve: a pair of axially aligned solenoids; a casing containing said solenoids and projecting thereabove to form a chamber; a valve stem projecting through said 110 solenoids into said chamber; toggle arms mounted within said chamber and adapted to operate said valve stem; and electric contact members adapted to contact with said toggle arms to close electric circuits operating said solenoids. 115

In witness whereof I claim the foregoing as my own I hereunto affix my signature at Portland, county of Multnomah, State of Oregon, this 13th day of June 1923.

ARTHUR F. ERICKSON.
